Des. 228,007
Patented July 31, 1973

228,007

SEGMENTED FLOWER GUARD

Helen H. Fletcher, Rte. 7, Box 525W,
San Antonio, Tex. 78221

Filed Dec. 29, 1971, Ser. No. 213,788

Term of patent 14 years

Int. Cl. D11—02

U.S. Cl. D35—3 C

FIG. 1

FIG. 2

FIG. 3

FIG. 4

FIG. 1 is a side elevational view of a segmented flower guard showing my new design.

FIG. 2 is a top plan view of FIG. 1.

FIG. 3 is a side elevational view of another embodiment of the invention.

FIG. 4 is a top plan view of FIG. 3.

I claim:

The ornamental design for a segmented flower guard, substantially as shown.
